UNITED STATES PATENT OFFICE.

CHARLES SHUMAN, OF ROCKFORD, ILLINOIS.

NECK-YOKE.

SPECIFICATION forming part of Letters Patent No. 252,332, dated January 17, 1882.

Application filed August 10, 1881. (No model.)

To all whom it may concern:

Be it known that I, CHARLES SHUMAN, a citizen of the United States, residing in the city of Rockford, in the county of Winnebago and State of Illinois, have invented a new and useful Improvement in Neck-Yoke Rings, of which the following is a specification.

My invention relates to neck-yokes employed mainly in connection with pleasure-carriages or other light vehicles; and its object is to provide a reliable anti-rattling or still neck-yoke connection with the tongue of vehicles at a small cost. To this end I have designed and constructed the center mountings of a neck-yoke, represented in the accompanying drawings, in which--

Figure 1 is an isometrical representation of the forward portion of a carriage-pole and central portion of a neck-yoke in which my improved mountings are employed. Of these parts, Fig. 2 is a vertical central section lengthwise of the pole. Fig. 3 is an isometrical representation of the leather-lined ring to receive the socket end of the carriage-pole. Fig. 4 is an isometrical representation of the ring-clasp in which the leather-lined ring is swiveled. Fig. 5 is an isometrical representation of the cap portion of the clasp. Fig. 6 is the form of the leather lining cut from the sheet.

In the figures, A represents the forward end portion of a carriage-pole fitted with the pole-socket B in the usual manner, and which pole-socket is provided with the usual oblique flange, a.

At C is represented the ring which receives the pole-socket. This ring is of proper oblique form to engage the oblique flange on the pole.

At b is represented a segment-shaped lining cut from suitable leather, bent and placed in the ring, to which it is fixed by means of suitable rivets, preferably of copper. The inner and outer curves of this segment are the same, which give to the segment a greater width at its center than at its ends, and is cut from the sheet without waste. This lining is placed in the ring to have its ends meet on the upper side of the ring, and consequently its wider portion will be in the narrower under portion thereof, and is so placed that it is flush with its forward edge, and the enlarged portion thereof will overlap the edge of the narrow

portion of the ring, forming a cushion, c, to engage the oblique flange on the pole-socket. This ring is provided on its upper and under opposite sides with stud-like journals d and e, 55 projecting therefrom in position to engage suitable openings in the ring-clasp, prepared to receive them.

At D is represented a clasp-ring provided on its under side with a hole, h, to receive the 60 stud-journal d of the lined ring, and the upper side of this clasp-ring is provided with a semi-bearing, k, to receive the upper stud-journal, e, of the lined ring. This clasp-ring is of sufficient size to permit the lined ring to oscillate 55 therein on its journal-supports. The upper portion of this ring is provided with a clasp-arm, E, which is of suitable curve to receive and embrace the under central portion of the neck-yoke.

At F is represented a curved clasp-arm fitted at its lower portion with a semi-bearing, l, to engage the forward portion of the stud-journal bearing e of the lined ring, and which, in connection with the semi-bearing k of the clasp-ring, furnishes the complete bearing of the upper stud-journal, e, of the lined ring. These clasp-arms are provided at proper points with suitable holes to receive suitable rivets, and serve to fix the parts to each other and to fix 80 them to the bar or wood portion of the neck-yoke, and the parts thus constructed are put in position by first placing the ring which receives the leather lining in position in its bearings in the clasp-ring and then fixing the two 85 parts of the clasp firmly to each other by means of sufficient rivets n, passed through the parts and properly riveted. The leather lining, previously prepared, is then put into the ring and fixed in position by suitable rivets, as seen at 90 o, which fits these parts to be placed upon the wood portion of the neck-yoke.

At H is represented the wood portion of the neck-yoke, which is of the usual form, turned from suitable material. This wood portion is 95 passed endwise into the ring portion formed of the clasp-arms D and E, which are of malleable material, and which are then pressed, hammered, or otherwise fitted to the wood, and then fixed in position thereon by sufficient 100 rivets and screws, as represented at p and s, which completes this central portion of the

yoke. The curve of these portions is such that in use the under portion of the clasp E will come in contact or rest on the rear portion of the pole-socket, operating to relieve the device 5 from the severe strain common to neck-yokes which are supported above the pole; and by means of the open or two-part clasp-arms to embrace the wood, I am enabled to fix the clasps firmly thereto, notwithstanding slight variations in their size, arising from the shrinkage of the wood or imperfect mechanical construction.

I claim as my invention—

1. The ring C, formed wider at the top than 15 at its under side, and provided with a leather or other equivalent lining, b, fitting the upper side of said ring, but projecting below the under side thereof to form the flange c, substantially as set forth.
2. The combination, with the socket B and 20

the flange a, of the ring C, having its rear side beveled and provided with a leather or other equivalent lining, the latter having a flange, e, which bears against the flange a, substantially as set forth.

25

3. The combination, with the ring C, having studs d and e, of a leather or other equivalent lining, b, having the flange c, the clasp-ring D, adapted to fit over the ring C, and provided with an opening, h, to receive the stud d, a 30 semi-bearing, k, for the stud e, and a clasp-arm, E, passing under the neck-yoke and arranged to bear on the pole, and a clasp arm, F, secured to the front of the neck-yoke and provided with a stud, l, to complete the bearing for the stud e, substantially as set forth.
